ATT'Y.

UNITED STATES PATENT OFFICE.

GEORGE W. SOUTHWICK, OF FRANKLIN, MASSACHUSETTS.

VEHICLE-TIRE.

SPECIFICATION forming part of Letters Patent No. 678,055, dated July 9, 1901.

Application filed May 23, 1901. Serial No. 61,532. (No model.)

To all whom it may concern:

Be it known that I, GEORGE W. SOUTHWICK, of Franklin, county of Norfolk, and State of Massachusetts, have made certain 5 new and useful Improvements in Vehicle-Tires, of which the following is a description sufficiently full, clear, and exact to enable any person skilled in the art or science to which said invention appertains to make and use 10 the same, reference being had to the accompanying drawings, forming a part of this specification, in which—

Figure 1 is a vertical transverse section of a bicycle-tire, showing my improvement; Fig. 15 2, a perspective view of the inner rigid air-chamber tube, showing the joint; and Fig. 3, a plan view of a section of the said tube.

Like letters of reference indicate corresponding parts in the different figures of the 20 drawings.

My invention relates especially to an improvement in bicycle-tires, and particularly to the formation of a rigid non-puncturable air-chamber inside of the outer elastic casing, 25 the object being to produce a tire of the requisite resiliency and, in addition, of the enlarged diameter deemed essential without making the same inflatable.

In carrying out my invention I provide a 30 tubular inner casing of rigid non-puncturable material which forms an air-chamber that avoids the objectionable features of excess weight, which militate against the use of what is known as the "solid" tire, without decreasing the size deemed desirable in the pneumatic tire.

The nature and operation of the device will be readily understood by all conversant with such matters from the following explanation.

40 In the drawings, A represents a wheel-felly of the ordinary grooved class and in which the spokes b are secured radially. The outer tire-casing C is the usual rubber tube thickened at the tread f and secured to the felly 45 or rim A by cementing. Within this casing C, I dispose a cylinder D, bent into a circle or ring of such diameter that it will seat tightly into the felly-groove. This tubular ring is made of two members h i, of wood, said members being substantially semicircular in cross- 50 section and chamfered or beveled at their

edges k, so that when joined they will register and the upper member h be prevented from slipping laterally on its companion. In order to bend these transversely semicircular strips longitudinally into the circle desired, I check or saw-kerf them at g laterally across the apex of their outer surfaces. They are then steamed and bent into the required form, these kerfs permitting sufficient take-up for 60 the inner member i and expansion for the outer member h. It will be understood that said kerfs do not extend through the thickness of either member, nor to their edges k.

Of course the diameter of the tubular ring 65 D necessary is known, and as a portion of the members are bent into the required arc they are secured together by screws or rivets m at frequent intervals. The space between said tubular wooden ring and the outer casing C is filled with sponge-rubber p or alternate layers of felting-rubber, and, in fact, any desired elastic material may be here disposed. This padding is secured to the outer face of the ring member h. Before the ends 70 of said ring are brought together it is passed longitudinally into the casing C through a slit in the casing-wall, said casing having been first disposed on the felly, the ends of the members h i, respectively, butting each 75 other at r t, as in Fig. 2, each member thereby overlapping the joint of the ends of its companion member. A metallic band V is then secured around the joint thus formed after said ring has been taken up sufficiently 80 to crowd it tightly into the felly-groove.

The outer casing, in addition to the cement employed, is firmly held to the felly by the wooden tubular ring and after the slit therein is healed need never be removed from said 90 felly until worn out, for puncturing has no effect whatever other than to penetrate the rubber. Even if said puncture is severe enough to penetrate the wooden tube no harm is done, as there is no escape of air, which in 95 said tube is only at atmospheric pressure. In fact I provide a tire which has all the advantages of size of the pneumatic, is sufficiently light, has none of the disadvantages of the solid tire, and in which there is greatly- 100 increased resiliency over said solid tire.

The disposition of the wooden tube within

the casing is a skilful operation and involves a process upon which I intend hereafter to apply for Letters Patent.

Of course it will be understood that the air-tube D might be constructed of other material than wood; but in addition to involving greater weight they are more expensive and in some degree impracticable. Moreover, the padding *p* may be omitted and the tube en-
10 gaged direct with the casing; but I deem this unadvisable.

Having thus explained my invention, what I claim is—

1. In a vehicle-tire a rubber outer casing; 15 an air-chamber therein comprising a hollow ring of wood formed of two members semi-circular in cross-section and secured together circumferentially.

2. In a tire of the class described a rigid air-chamber, D, formed of two annular members, *h*, *i*, kerfed laterally in their outer faces. 20

3. In a tire of the class described a rigid air-chamber, D, formed of two annular members, *h*, *i*, kerfed laterally in their outer faces and having their edges chamfered substantially as and for the purpose specified. 25

4. The felly; the rubber casing, C; the wooden annular tube, D, within said casing and drawn into the felly-groove; and the elastic padding between said tube and casing all being combined and arranged to operate substantially as described. 30

GEORGE W. SOUTHWICK.
